(57) **CLAIM**

The ornamental design for a funnel, as shown and described.

DESCRIPTION

FIG. 1 is a perspective view of a funnel embodying our design, with the semicircular recesses along the top margin of the funnel, the hanger-receiving hole at the rear of the top margin, the corrugations along the sidewall, and the circumferentially-spaced, stepped ribs adjacent the outlet of the funnel being shown in broken lines for illustrative purposes only and forming no part of the claimed design;

FIG. 2 is an end elevation view of the funnel depicted in FIG. 1;

FIG. 3 is a side elevation view of the funnel depicted in FIGS. 1 and 2, with the opposite side elevation being a mirror image thereof;

FIG. 4 is an end elevation view of the funnel opposite that depicted in FIG. 2;

FIG. 5 is a top elevation view of the funnel depicted in FIGS. 1-4; and,

FIG. 6 is a bottom elevation view of the funnel depicted in FIGS. 1-5.
